DESIGN FOR A COMBINATION TOBACCO HUMIDOR AND PIPE TRAY

Joseph Gottlieb, New York, N. Y.

Application September 4, 1948, Serial No. 148,483

Term of patent 3½ years

(Cl. D85—8)

To all whom it may concern:

Be it known that I, Joseph Gottlieb, a citizen of the United States and a resident of 235 East 196 Street, Borough of Bronx, city, county, and State of New York, have invented a new, original, and ornamental Design for a Combination Tobacco Humidor and Pipe Tray, of which the following is a specification, reference being had to the accompanying drawing, forming a part thereof.

On the drawing:

I claim:

The ornamental design for a combination tobacco humidor and pipe tray, as shown.

JOSEPH GOTTLIEB.
